GARMENT

Albert N. La France, Paterson, N. J., assignor to
 The Manhattan Shirt Company, New York,
 N. Y., a corporation of New York

Application May 9, 1941, Serial No. 392,645

7 Claims. (Cl. 2—234)

This invention relates to an improved slide fastener fly construction, the novel features of which will be best understood from the following description and the annexed drawings.

In the drawings, Fig. 1 is a front elevational view of a garment having a trouser fly construction embodying the principles of this invention, the garment illustrated being partially broken away to show the interior fly construction; Fig. 2 is a side elevational view of the garment shown in Fig. 1; Fig. 3 is an enlarged fragmentary rear view of the front of the garment shown in Fig. 1 and showing in rear elevational view the fly portion of the garment, the left fly being partially broken away to show more clearly the arrangement of the slider fastener in the garment; Fig. 4 is a view similar to Fig. 3 but showing the fly in opened position; Fig. 5 is a cross-sectional view taken along the line 5—5 of Fig. 3; Fig. 6 is a view similar to Fig. 5 showing the fly construction in partially opened condition; Fig. 7 is a cross-sectional view taken along the line 7—7 of Fig. 4; Fig. 8 is a view somewhat similar to Fig. 3 and showing in perspective a modified form of the invention, and Fig. 9 is a cross-sectional view taken along the line 9—9 of Fig. 8 and showing in dotted outline the auxiliary closing means in opened position.

Referring more particularly to Figs. 1 to 7 of the drawings, the right front or front panel of a trouser garment is generally designated 10, while the left front or front panel of the garment is generally designated 11, such front panels 10 and 11 extending forwardly from the side seams of the garment and forming the front of the garment. A waistband 12 is secured to the upper edges of the left and right front panels in a known manner, one end of the waistband being provided with a button hole 13 and the other end thereof designated 14 being provided with a co-operating button 15. As is shown more clearly in Fig. 4 of the drawings, the end of the waistband designated 14 projects beyond the inner edge of the right front panel 10 which is substantially in alignment with the center seam 16 of the garment, the button 15 carried thereby being thus positioned, in the closed condition of the garment, slightly to the left of the center seam 16. The inner edge of the right front panel is a folded edge formed by folding inwardly the material of which such front panel is constituted to form a folded edge portion 17 extending along the inner edge of such panel 10 from the waistband 12 to the center seam 16, the free edge of the folded portion 17 being overedged to prevent unraveling 55

of the material. The inner edge of the left front panel 11 is likewise a folded edge produced by folding the material of such front panel inwardly to form an inner folded portion 18 extending from the waistband 12 to the center seam 16. The folded edge of the left front panel 11, unlike the folded edge of the right front panel, is in alignment with the inner edge of the adjacent end of the waistband 12. The inner folded portion 18 has a width substantially greater than the width of the folded portion 17 of the right front panel, being in fact, from 2½ to 3 times wider than the latter. Positioned intermediate the folded portion 18 and the left front panel 11 is a layer of lining material 19 which is secured to the folded portion 18 by a line of stitches 20 and to both the folded portion 18 and the front panel 11 by a line of stitches 21.

Secured to the inner face of the folded portion 17 as by two lines of stitches 22 and 23 is one stringer 24 of a slide fastener structure, the said stringer 24 being so attached that the interlocking elements 25 connected thereto extend outwardly from the inner folded edge of the right front panel 10. The two lines of stitches 22 and 23 extend throughout the entire length of the stringer 24, the line of stitches 23 penetrating only the stringer 24 and the folded portion 17, while the line of stitches 22 extend through both the stringer 24, the folded portion 17 and the right front panel 10 along a longitudinal line positioned just within the inner folded edge of the right front panel 10. The row 35 of fastener elements 25 on stringer 24 are adapted to interlock in interfingering relation with a row of fastener elements 26 provided on a second stringer 27, such interlocking engagement being controlled by a slider 28 which is manipulated 40 manually along the longitudinal rows of elements 25 and 26, as is well known in the art. The stringers 24 and 27 are joined together at their lower ends by a bottom stop and are also connected at a point above such stop by a cross tape 45 29 positioned on the interior of the slider and having an upwardly directed beaded or reinforced edge extending across the path of movement of the slider 28 and attached to catch the slider on the latter's downward movement to prevent unnecessary wear at this portion of the slide fastener structure.

The stringer 27 of the slide fastener is secured by a line of stitches 30 to the left fly 31 which is composed of a single piece of material folded

along its longitudinal central line to produce a

longitudinally extending folded edge, the side edges of such material being united together by an overedging thread, as is shown more clearly in Figs. 5 to 7 of the drawings. The stringer 27 is positioned on the front layer of the fly 31 intermediate the longitudinally extending edges of the latter. The left fly 31 is secured to the inner folded portion 18 so that its folded edge projects outwardly a substantial distance from the inner folded edge of the left front panel 11 and is attached to the upper end of such folded portion 18 by a horizontal line of stitches 32 positioned adjacent to and in parallelism with the lower edge of the waistband 12, a vertical line of stitches 33 extending from the line of stitches 32 along a line positioned closely adjacent to the inner or attached ends of the elements 26 on the stringer 27 down to a point approximately one-third the length of the fly member 24 and a horizontal or transverse line of stitches 34 extending from the lower terminal end of the line of stitches 33 towards the attached edges of the fly 31 and in parallelism with the line of stitches 32. Thus the stringer 27 which is sandwiched in between the folded portion 18 and the left fly 31 is securely connected to both members from the waistband 12 down to a point approximately one-third its length and from such point to the lower end thereof is attached only to the left fly 31, so that, the remaining portion of the stringer 27 and consequently the portion of the left fly 31 to which it is attached, may be separated from the adjacent portions of the left front panel 11 and its folded portion 18. The lower end of the left fly 31 is connected to the front panels 10 and 11, the inner folded portions 17 and 18 and the stringers 24 and 27 by a transverse line of stitches 35 which is disposed beneath the lower edge of the cross bar 29, as is shown more clearly in Fig. 4 of the drawings. From the line of stitches 35 the lower terminal end of the left fly 31 is also secured to such parts by the center seam 16. Intermediate the two transverse lines of stitches 34 and 35, the left fly 31 is provided with the male part 36 of a snap fastener adapted to engage with a female snap fastener part 37 attached to the inner folded portion 18 to close the opening between the fly 31 and the left front panel 11 intermediate such lines of stitches 34 and 35.

From the foregoing it will be seen, that there has been provided a new and improved slide fastener trouser fly construction embodying a slide fastener attached to a left fly which itself is attached only partially to the left front panel of the garment so that even when the slide fastener is fully closed access may readily be made into the interior of the garment simply by unlocking the auxiliary closure or snap fastener. The assembly of this fly construction is accomplished by first folding inwardly the folded portion 17 to form a fold along the inner edge of the right front panel 10. A strip of lining material 19 conforming in shape to the folded portion 18 of the left front panel 11 is then secured to such folded portion 18 by the line of stitches 20 and a line of stitches 21 which joins also the inner salvaged edge of such folded portion 18 to the front panel 11. A slide fastener structure comprising the stringers 24 and 27, their associated rows of elements 25 and 26, the slider 28 and the cross bar 29, is then attached to the fly member 31 by sewing the stringer 27 to such member by the line of stitches 30. The stringer 24 of this unit is then attached to the folded portion 17 by means of the line of stitches 23 and to the folded portion 17 and 75

the right front panel 10 by means of the line of stitches 22. The left fly member 31 with the attached stringer 27 is then secured to the upper end of the folded portion 18 by means of the lines of stitches 32, 33 and 34 and to the lower end of such folded portion by the transverse line of stitches 35. The pair of substantially parallelly disposed lines of stitches forming the center seam 16 are thereupon made to secure the lower terminal end of the fly member 31 below the transverse line of stitches 35 to the parts of the garment previously pointed out, thus leaving the outer folded edge portion of the fly 31 free for its entire length.

While by the foregoing a preferred form of the invention has been described, it will be understood that changes and modifications therein may be made within the scope of the invention. For example, instead of attaching the stringer 27 of the slide fastener to the forward face of the fly member 31, as is illustrated in Figs. 1 to 7 of the drawings, such stringer may be secured to the rear face of the fly member, as is illustrated in Figs. 8 and 9 of the drawings, thus providing a protection against contact with the fastener elements 25 and 26 while entry is made into the interior of the garment. In this construction, the left fly element 31 is preferably reinforced by a strip of lining material 38 which may be first secured intermediate the folded portions of such member in the formation of such member. Preferably also in this construction, there is attached to the rear folded edge portion of the right panel 10 a fly member 39 composed of two layers of cloth whose ends have been first stitched together with the faces of the material together and then folded to provide a folded edge, the free edges of the two layers of folded material being then attached to the right panel 10 and to the stringer 24 by the line of stitches 22 which extend longitudinally of such stringer adjacent to the clamping ends of the interlocking elements 25 thereof.

I claim:

- 45 1. In combination with a garment having adjacent overlapping edge portions providing an opening, the garment material at such edge portions being folded inwardly and the inner fold of the outer, overlapping edge portion having a width greater than the inner fold of the overlapped edge portion, a slide fastener stringer attached to the overlapped edge portion throughout its entire length, a backing member attached to said overlapping edge portion, a second stringer attached to said backing member throughout its entire length, and a slider longitudinally slid able on the interlocking elements of said slide fastener stringers for securing said stringers together, said backing member being attached to said overlapping edge portion at its ends and for a portion of its length from one of such ends, leaving the remainder of such backing member unattached and free of said overlapping edge portion, whereby entry may be made between said adjacent edge portions into the interior of the garment when the slide fastener stringers are in their fully closed condition.
- 50 2. In a combination such as is defined in claim 1, a pair of spaced lines of stitches connecting said backing member to said overlapping edge portion of the garment, said lines of stitches extending transversely to the length of said backing member and defining the limits of the opening between said overlapping edge portion and said backing member and auxiliary fastening

means connected to said overlapping edge portion and said backing member intermediate said spaced lines of stitches and operable independently to close the opening between such members.

3. In a trouser fly construction including overlapped right and left front portions of a trouser garment, a slide fastener stringer attached to said right front portion throughout its entire length, a left fly attached to said left front portion, a second fastener stringer attached to said left fly throughout its entire length, and a slider longitudinally slidable on the interlocking elements of said slide fastener stringers for securing said stringers together, said left fly being attached to said left front portion at its top and bottom ends and from its top end down to a point spaced from such end less than half the length of said left fly, leaving the remainder of the fly unattached and free of said left front portion, whereby entry may be made between said left fly and said left front portion into the interior of the garment when the slide fastener stringers are in their fully closed condition.

4. In a trouser fly construction such as is defined in claim 3, in which said left fly is connected to said left front portion at its ends by transverse lines of stitches and intermediate its ends by a transverse line of stitches disposed in substantial parallelism with said top and bottom lines of stitches, said intermediate and top lines of stitches being connected by a line of stitches extending longitudinally of the left fly and attaching the latter to said left front portion.

5. In a trouser fly construction such as is defined in claim 3, in which said second-mentioned stringer is attached to the front face of said left fly and includes auxiliary fastening means connected to said left fly and said left front portion intermediate the ends of the opening therebe- 40

tween and operable independently to close the opening between such members.

6. In a trouser fly construction such as is defined in claim 3, in which said second-mentioned stringer is attached to the rear face of said left fly, whereby insertion may be made into the interior of the garment without contacting the fastener elements of the stringers, and including a right fly attached to said right front portion and underlying said second-mentioned stringer and said left fly.

7. In combination with a garment having adjacent overlapping edge portions providing an opening, a series of fastener elements attached to the overlapped edge portion throughout the entire length of the opening, an elongated backing member extending lengthwise of the opening, means attaching said backing member to said overlapping edge portions at its ends and for a portion of its length from one of such ends, leaving the remainder of such backing member unattached and free of said overlapping edge portion, a second series of fastener elements attached to said backing member, said second series of elements being complementary to the elements of said first series and adapted to cooperate with the same to secure said backing member to said overlapped edge portion, and independent complementary fastener devices connected to the unattached portion of said backing member and to the overlapping edge portion, said fastener devices cooperating to releasably connect said unattached portion of the backing member to the overlapping edge portion and adapted to be disengaged to permit entry into the interior of the garment without disengaging the series of complementary elements connecting the backing member and the overlapped edge portion.

ALBERT N. LA FRANCE.
